W. H. SAUVAGE

SLACK ADJUSTER

Filed Feb. 6, 1920

UNITED STATES PATENT OFFICE.

WILLIAM H. SAUVAGE, OF FLUSHING, NEW YORK, ASSIGNOR, BY MESNE ASSIGNMENTS, TO GOULD COUPLER COMPANY, OF NEW YORK, N. Y.

SLACK ADJUSTER.

Application filed February 6, 1920. Serial No. 356,755.

To all whom it may concern:

Be it known that I, WILLIAM H. SAUVAGE, a citizen of the United States, residing at Flushing, Long Island, in the county of 5 Queens and State of New York, have invented certain new and useful Improvements in Slack Adjusters, of which the following is a specification.

This invention relates to improvements 10 in slack adjusters and more particularly to slack adjusters adapted to be associated with the brake rigging of the trucks of railway vehicles, although it is to be understood that the invention without modification 15 may be applied to any part of the brake rigging where it is desired to take up the slack involving relative movement between the effective ends of two connected parts of the brake rigging.

20 One of the objects of the present invention is to provide an improved form of slack adjuster of simple and practical construction which will be reliable and efficient in use and operation.

25 A further object is to provide an improved form of slack adjuster which may be inexpensively manufactured and assembled and which is not likely to be affected by atmospheric conditions due to freezing, rusting or dirt and dirt of the road.

30 Other objects will be in part obvious and in part hereinafter pointed out.

In the accompanying drawings, wherein is shown one of various possible applications 35 and forms of the present invention,

Figure 1 is an elevational view showing such parts of the brake rigging and truck framing as is necessary to understand the present invention.

40 Figure 2 is an enlarged detail sectional plan view of certain parts of the mechanism.

Referring now to the drawings in detail, 45 a central bolster 6 and wheels 7 with which shoes 8 are adapted to coact on application of the brakes. These shoes are carried by

brake beam 10 having struts 11.

50 A live lever 12 is connected by means of a pull rod 13 at the point 14 with any suitable source of power adapted to urge the upper end of the live lever relatively towards the left on an application of the brakes.

The lower central part of the live lever is pivotally mounted in the strut 11 while its 55 lower end is pivotally connected at 15 with the tubular part 16 of the two part push rod. The other part or rod proper 17 is pivotally connected at 18 with the lower part of the dead lever 20, the upper end of 60 the lever being pivotally connected in any one of a series of openings 21 in a support 22 pivotally connected at 23 with the truck frame. The central part of the dead lever is of course mounted in the strut 11. 65

These parts are all of well-known construction and to those familiar in the art it will readily be seen that on application of the brakes, motion will be transmitted through the push rod 16 to dead lever 20 70 in order to carry the brake shoes 8 into engagement with the peripheries of the wheels 7.

Parallel to the push rod 16 is an adjusting rod 24 having a slotted or lost motion connection 25 with pivot pin 26 connecting the live lever with the strut 11. This slot is for the purpose of insuring brake shoe-clearance on release of the brakes and of permitting a normal application of the brakes to 80 take place without operating the slack adjuster unless there is excess movement. The opposite end of this adjusting rod 24 is supported by a housing 27 and held in relatively locked engagement therewith by 85 means of lock nuts 28. This housing slidably engages rod 17 and carries one or more dogs 30 normally held in canted relation with respect to the rod 17 by means of a coil spring 31 within the housing. The tubular member 16 is also provided with a housing 32 in fixed position having a plurality of dogs 33 held in canted relation by means of spring 34, the parts being so positioned and arranged that a relative inward 90 telescopic movement of the rod 17 is positively prevented during application of the brakes but an outward movement thereof can freely take place when necessary to extend push rod in order to permanently take 95 up the excess slack.

Interposed between the housings 27 and 32 is a coil spring 35 adapted to extend the rod 17 relatively towards the right in order to insure the taking up of the slack and release of the brakes. 105

A return spring 36 is associated with the mechanism in any desired manner as between the truck frame and the upper part of the live lever 12 whereby the lever is restored to normal position upon release.

The operation of this device is substantially as follows:

On application of the brakes the upper part of the live lever moves towards the left, reacts through the telescopic push bottom rod upon the dead lever 20 thereby to bring the brakes into applied position. If excess travel takes place exceeding that provided for by the slot 25 then this motion will be transmitted through the adjusting rod 24 to move the housing 27 towards the left and compress the spring 35, the dog 30 being so mounted as to slide freely towards the left along the rod 17. On release 20 of the brakes the brake shoes first drop clear of the wheels as provided for by the lost motion slot 25 after which a continued rearward movement of the live lever 12 under the action of the return spring 36 will transmit the motion through the adjusting rod 24 and housing 27 to move the rod 17 outwardly being aided, of course, by the spring 35 which was compressed during application. In this case the dog 30 bites into the rod 17 to form a positive engagement therewith and cause the rod 17 to slide freely outward or towards the right with respect to the dogs 33 which thereafter permanently hold the excess slack due 35 to wear of the parts. Thus the slidably mounted housing and dog adjustment on the effective end of the adjusting rod permit free sliding movement of these parts leftwardly along the push rod to the extent of excess travel of the brake shoes and the extreme leftward point of travel becomes the point at which the dog grips on the push rod upon release of the brakes.

From the above it will be seen that the present invention provides a simple and practical slack adjuster mechanism having relatively few parts which may be inexpensively manufactured and assembled. The device is exceedingly durable and reliable and there is little or no danger of the parts freezing, rusting or sticking into a non-operative position. The invention is believed to accomplish all the objects and advantages herein set forth.

It is believed that the above will so fully reveal the gist of the present invention that others can by applying current knowledge readily adapt the same to various uses and modifications, and the appended claims are intended to cover all of the generic and specific features thereof that may be comprehended within the range of equivalency.

What I claim is:

1. In a slack adjuster mechanism, in combination, live and dead levers, a two-part

telescopic push-rod connecting said levers, an adjusting rod lying substantially parallel thereto and connecting with one of said parts, the connection between the effective ends of the parts of said telescopic push rod and between the adjusting rod and one of the parts of said telescopic push rod each comprising a housing and a holding dog, said housings being urged apart by spring means and the dogs being so mounted as to permit relative movement of the two parts of the telescopic rod in one direction and of the adjusting rod and its housing on said telescopic push rod in the other direction.

2. In a slack adjuster mechanism, in combination, live and dead levers, a two part telescopic push-rod connecting said levers, an adjusting rod lying substantially parallel thereto and connecting with one of said parts of said telescopic push rod and between the adjusting rod and one of the parts of said telescopic push rod each connection comprising a housing and a holding dog, the dogs being so mounted as to permit relative movement of the two parts of the telescopic rod in one direction and the adjusting rod and the other part of said telescopic push rod in the other direction and a spring to aid in returning the parts to normal position associated with said push rod.

3. In a slack adjuster mechanism, in combination, live and dead levers, a two-part telescopic push rod connecting the lower ends of said levers and two sets of holding dogs urged apart by a spring member and coacting with one of the parts of said push rod, an adjusting rod positioned substantially parallel to said push rod and operatively associated with one of said holding dogs, whereby the push rod is freely moved in one direction with respect to one and in the opposite direction with respect to the other.

4. In a slack adjuster mechanism, in combination, live and dead levers, a two part telescopic push rod connecting the lower ends of said levers, two sets of holding dogs coacting with one of the parts of said push rod, retained in continuous operative position whereby the push rod is freely moved in one direction with respect to one and in the opposite direction with respect to the other, an adjusting rod connected with one of said dogs adapted to move the same when excess travel occurs, and a spring adapted to urge said adjusting rod in reverse direction.

5. In a slack adjuster mechanism, in combination, live and dead levers, a two part telescopic push rod connecting the lower ends of said levers, a housing having a dog therein adapted to prevent relative movement on application of the brakes, a sec-

- ond housing and dog coacting with one of the parts of said push rod adapted to be moved therealong when excess travel occurs and to change the relative length of said push rod on release of the brakes if excess travel has occurred, and spring means adapted to effect positive movement of the brakes to normal releasing position and to prevent relaxing the push rod position.
6. In a slack adjuster mechanism, in combination, live and dead levers, a two part telescopic push rod connecting the lower ends of said levers, a housing having dogs therein adapted to prevent relative movement on application of the brakes, a second housing and dog coacting with one of the parts of said push rod adapted to be moved therealong when excess travel occurs and to change the relative length of said push rod on release of the brakes if excess travel has occurred a spring urging said housings apart, an adjusting rod connected with said last mentioned dog at one end and having a lost motion connection with the live lever at its opposite end.
7. In a slack adjuster mechanism, in combination, live and dead levers, a two part telescopic push rod connecting the lower ends of said levers, a housing having a dog therein adapted to prevent relative movement on application of the brakes, a second dog coacting with one of the parts of said push rod adapted to be moved therealong when excess travel occurs and to change the relative length of said push rod on release of the brakes if excess travel has occurred, an adjusting rod connected with said last mentioned dog at one end and having a lost motion connection with the live lever at its opposite end, and spring means adapted to restore the parts to normal position.
8. In an automatic slack adjuster, the combination with a pair of brake levers and a bottom rod comprising longitudinally adjustable members connected to the ends of said levers, of a spring acting on one of said members, a rod operated by excess movement of the brake levers in applying the brakes for compressing said spring, and a clutch mechanism for preventing relative longitudinal movement of said members in one direction.
9. In a slack adjuster mechanism, in combination, live and dead levers, a two part telescopic push rod connected with the lower end of said levers, positively acting holding means adapted to prevent the relative change in length of said push rod during the application of the brakes, a second positively acting holding means associated with one of said parts in the push rod, and adjusting rod connected therewith at one part and having a lost motion connection with the live lever at another part adapted to move relative to the part of the push rod with which it is connected when excess slack occurs during application of the brakes and to move said part to vary the length of said push rod on release of the brakes if excess travel occurs and spring means adapted to insure the 70 operation of said adjuster.
10. In a slack adjuster mechanism, in combination, live and dead levers, a two part telescopic push rod connected with the lower end of said levers, positively acting holding 75 means adapted to prevent the relative change in length of said push rod during the application of the brakes, a second positively acting holding means associated with one of said parts of the push rod, an adjusting rod connected therewith at one part and having a lost motion connection with the live lever at another part adapted to move relative to the part of the push rod with which it is connected when excess slack occurs during the 80 application of the brakes and to move said part to vary the length of said push rod on release of the brakes if excess travel occurs, and spring means adapted to insure the 85 operation of said adjuster, said means including a coil spring directly associated with and acting between said positive holding means.
11. In a slack adjuster mechanism, in combination, live and dead levers, a two-part telescopic push-rod connecting said levers, an 90 adjusting rod lying substantially parallel thereto and connecting with one of said parts, the connection at the effective end of one part of said telescopic push-rod and at the effective end of said adjusting rod comprising each a housing and holding dog means, mounted to permit free relative movement of the two parts of the telescopic rod in one direction and of the adjusting rod with its housing in the other direction, said 95 housings urged apart by an interposed spring member.
12. In an automatic slack adjuster, the combination with brake levers, of a bottom rod comprising a casing connected to the end of one lever, a member connected to the end of the other lever and extending into and movable relatively to the casing, a spring acting on said member, means operated by 100 excess movement of the brake levers in applying the brakes for compressing said spring, and a device for locking said member against movement relative to the casing in applying the brakes.
13. In an automatic slack adjuster, the combination with a pair of brake levers and a bottom rod comprising longitudinally adjustable members connected to said levers, of a spring acting on one of said members, a rod operated by excess movement of the 105 brake levers in applying the brakes for compressing said spring, and a clutch mechanism for preventing relative longitudinal movement of said members in one direction.
14. In an automatic slack adjuster, the 110
15. In an automatic slack adjuster, the combination with a pair of brake levers and a bottom rod comprising longitudinally adjustable members connected to said levers, of a spring acting on one of said members, a rod operated by excess movement of the 115 brake levers in applying the brakes for compressing said spring, and a clutch mechanism for preventing relative longitudinal movement of said members in one direction.
16. In an automatic slack adjuster, the 120
17. In an automatic slack adjuster, the combination with a pair of brake levers and a bottom rod comprising longitudinally adjustable members connected to said levers, of a spring acting on one of said members, a rod operated by excess movement of the 125 brake levers in applying the brakes for compressing said spring, and a clutch mechanism for preventing relative longitudinal movement of said members in one direction.
18. In an automatic slack adjuster, the 130

combination with brake levers, of a bottom rod comprising a casing connected to the end of one lever, a member connected to the other lever and extending into and movable relatively to the casing, a spring acting on said member, means operated by excess movement of the brake levers in applying the brakes for compressing said spring, and a device for locking said member against

movement relative to the casing in applying the brakes.

In testimony whereof I affix my signature in the presence of two witnesses.

WILLIAM H. SAUVAGE.
